UNITED STATES PATENT OFFICE.

JOSEPH A. MACK, OF MINTURN, COLORADO.

BURGLAR-ALARM LOCK.

Application filed April 22, 1922. Serial No. 555,981.

To all whom it may concern:

Be it known that I, JOSEPH A. MACK, a citizen of the United States of America, residing at Minturn, county of Eagle, and 5 State of Colorado, have invented certain new and useful Improvements in Burglar-Alarm Locks; and I do declare the following to be a full, clear, and exact description of the invention, such as will enable others 10 skilled in the art to which it appertains to make and use the same, reference being had to the accompanying drawings, and to the characters of reference marked thereon, which form a part of this specification.

15 This invention relates to combination locks and has reference to a lock that is constructed on the permutation principle and provided with means whereby a signal will be operated whenever the lock is tampered with by an unauthorized person.

It is well known that persons skilled in that particular art can open by skill or by force almost any lock that has been constructed and that therefore reliance cannot 25 be had on locks per se.

It is the object of this invention to provide a lock that shall be of simple yet rigid and substantial construction and which will be comparatively safe against 30 being opened by any one not conversant with the combination and manner of operating the same. I do not, however, rely entirely on the lock for protection but combine with the lock a signal and means for operating

35 the signal whenever the lock is tampered with. I am aware that it is old to make locks that will operate signals of some sort, but I provide my lock with a plurality of different elements which co-operate to operate the signal whenever any one of several 40 movable parts of the lock are disturbed in the least, and in this manner I provide a lock that will operate an alarm as soon as it is tampered with at all.

45 In order to more clearly describe my invention I shall have reference to the attached drawing in which:

Fig. 1 shows a perspective view of a door to which my lock and signal have been applied.

50 Fig. 2 is a section taken on line 2—2 Fig. 3.

Fig. 3 is a section taken on line 3—3 Fig. 2.

55 Fig. 4 is a section taken on line 4—4 Fig. 2.

Fig. 5 is a detail of the dial.

Fig. 6 is an assembly of the knobs and tumbler discs.

Fig. 7 is a view showing the proposed 60 signaling means and

Fig. 8 is a section taken on line 8—8 Fig. 3.

The same reference character will be used to designate the same parts throughout the 65 several views.

Numeral 1 represents a door which may be a safe door or a door of any other kind. Fitted to a door 1 is a lock 2 from which a rod or wire 3 extends to a lever 4 on 70 the opposite side of the door by means of which the alarm 5 is operated in a manner that will hereinafter be described.

My lock consists of a metal casing 6 having one side 7 thereof removable and provided with a door 8 the purpose of which will hereinafter appear. In Figs. 1, 3 and 4 I have shown my lock attached to the inside of a wooden or metal door 9. The locking mechanism consists of a bolt 10, which is 80 slidably mounted in an opening 11 in the front side of the lock casing and has its inner end guided by lugs 12. Bolt 10 has pivotally attached thereto a link 13 whose other end is secured to a crank pin 14 on 85 the end of spindle 15. On the outer end of spindle 15 I provide a handle 16 by means of which it may be rotated so as to reciprocate the bolt 10 in a manner which will be readily apparent.

In order to prevent the spindle 15 from being rotated in more than one direction I secure to the same by means of a pin 17, a ratchet 18 which is engaged by a pawl (Fig. 8). The ratchet teeth 20 are of such length 95 as to permit the pawl to be moved backwards and forwards a distance somewhat greater than the length of teeth 21. In order to lock the bolt 10 in protruding position I provide a plurality of tumblers 22, 100 23, 24 and 25. Each of these tumblers are provided with gear teeth 26 and a notch 27. The notches 27 are of a width which will permit the inner end of bolt 10 to enter therein and of sufficient depth to allow the bolt to be withdrawn until its outer end is flush with the outside of the lock 6. In order to rotate each one of the tumblers independently and to any extent desired I secure tumbler 22 to the lower, or inner end 110 of a tubular member 27 to the outer end of which a flange 28 is secured. Tumbler 23

is connected to the lower end of tubular member 29 the other end of which is provided with a flange 30. Tumbler 24 is secured to the inner end of tubular member 31 to the outer end of which a flange 32 is secured while tumbler 25 is secured to the inner end of rod 33 whose outer end has a flange or head 34. By rotating flange 28 the tumbler 22 can be rotated any amount 10 desired, and in a similar manner the tumblers 23, 24 and 25 may be rotated by means of the members 30, 32 and 34 respectively. It is apparent that some means must be provided to prevent all of the tumblers from 15 being rotated whenever any one of the flanges is turned and for this purpose I have provided each tumbler with a detent spring 35 which engages the circumference thereof with sufficient force to prevent the friction 20 between the various surfaces from moving the same. By means of the dial 36 and the graduations on the flanges 28, 30, 32, and 34 the tumblers may be readily arranged so that the notches 27 will register to receive 25 the end of bolt 10.

If I were interested in the locking means alone the elements above described would constitute an operative combination but I desire to provide my lock with means that 30 will operate the signal 5 whenever an unauthorized person shall tamper with the same, and for this purpose I provide the following mechanism. As before pointed out the tumblers are each provided with 35 gear teeth 26 which perform a double function. In the first place teeth 26 prevent the end of the bolt 10 from being held in contact with the tumblers while they are rotated for the reason that when the bolt 40 is reciprocated inwardly the teeth 21 will engage teeth 26 and prevent rotation of the tumblers. The second function of teeth 26 is to engage similar teeth on discs 37 of which there is one for each tumbler. Discs 45 37 are rotatably mounted on a common spindle 38 and have a segment thereof cut away as indicated at 39. When discs 37 are positioned as shown in Fig. 2 they are inoperative but if they are rotated so that the teeth 50 thereof engage with the teeth 26 they will be rotated whenever the tumblers are rotated.

For the purpose of adjusting the position of discs 37, I provide a door 8 in the side 55 7 of the casing; this door may be opened and the discs adjusted whenever it is desired to set them. Secured to each of the discs 37 is a wire 40 which is connected with wire 3. Whenever either one of discs 37 are 60 rotated wire 40 will be pulled and this in turn will pull wire 3 which moves the lever 4 and operates the signal 5.

On each side of the bolt 10 I provide a gear wheel 41 having a segment thereof removed as indicated at 42. Each wheel is

secured to the end of a spindle 43 which has on its outer end a knob 44. By rotating the knob 44 the gear wheels 41 may be rotated to any position. When the door is locked gears 41 are rotated in the direction 70 of the arrows until they engage with the gears on the side of the bolt 10. When the teeth of gears 41 engage those on the bolt, it is evident that any longitudinal movement of the bolt will rotate the wheels. 75 Wires 45 extend from points near the outer periphery of the wheels to wire 3 and therefore the rotating gears 41 will serve to operate the signal 5. Knobs 44 may be provided with a mark by which the operator is 80 enabled to determine the position of the gears 41. Detent springs 46 are arranged to co-operate with the gears 41 so as to hold them in any position to which they are set. At the rear edge of the door I provide a 85 lever 4 which is pivoted at P. A spring 47 is provided between the lower end of lever 4 and the door so as to hold it normally in the position shown in Fig. 7.

To the upper end of line 4 the end of wire 3 is connected and to the lower end there is pivoted a plunger 48 which is normally within the tube 49 in the door 1. When the wire 3 is pulled lever 4 will be rotated in a counter-clock-wise direction 90 and plunger 48 will be projected and will engage the end of another plunger 50 which is secured to the end of a pivoted pawl 60 which controls the signal.

The signal may be made in different ways 100 but I have shown a plate 61 on which is mounted a spindle 62 to which is rotatably secured a toothed disc 63. A spring 64 has its outer end secured to the disc at 65 and its inner end to the spindle. The spring is 105 put under tension or wound by rotating the disc in a clockwise direction and the pawl 60 engaging the teeth of the disc will keep the same from turning. Secured to the disc 63 is a finger 66. I secure a revolver 67 to 110 the plate 61 by suitable means and adjust the same so that the finger 66 will strike the trigger 68 and fire the revolver which may be loaded with a blank cartridge. By 115 suitable modification I may use a self cocking revolver and have it fired a number of times. I may also have the finger 66 operate a switch and sound an alarm at a distant place. As previously pointed out there are a large variety of ways in which an 120 alarm might be sounded and so I am not concerned in this case with the specific alarm or signalling means. I shall not further describe the same.

From the above description it will appear 125 that I have provided a combination lock of a substantial and serviceable design and have provided the same with means which will operate a signal or sound an alarm when any unauthorized person starts tam- 130

pering with the lock. If a person moves any one of the tumblers 22, 23, 24 or 25 he will rotate one of discs 37 and set off the alarm and if he turns the handle 16 he will 5 rotate gears 41 and sound the alarm. If he turns either one of knobs 44 he rotates the gears 41 and sounds the alarm while, if the lock is sprung by means of explosives the resultant disturbance will sound the alarm.

10 Having now described my invention what I claim is:

1. A lock comprising a bolt, means for reciprocating said bolt, a plurality of tumblers for preventing movement of the bolt 15 in one direction, notches in said tumblers adapted to receive the end of the bolt, means for rotating each tumbler independently of the others, gear teeth in the edges of said tumblers, a plurality of rotatably mounted 20 gear wheels having a segment removed from one side and mounted for engagement with the tumblers and means connected to each of said gears adapted to connect the same to a signal in such a manner that it will 25 function when either of the gears is rotated.

2. A lock comprising a bolt, means for reciprocating said bolt, a plurality of tumblers for preventing movement of the bolt in one direction, notches in said tumblers 30 adapted to receive the end of the bolt, means for rotating each tumbler independently of the others, gear teeth in the edges of said tumblers, a plurality of rotatably mounted gear wheels having a segment removed from 35 one side and mounted for engagement with the tumblers and a wire attached to each gear wheel said wire being adapted to operate a signal when the gears rotate.

3. A lock comprising a bolt, means for 40 reciprocating said bolt, a plurality of tumblers for preventing movement of the bolt in one direction, notches in said tumblers adapted to receive the end of the bolt, means for rotating each tumbler independently of 45 the others, gear teeth in the edges of said

tumblers, gear teeth on the end of the bolt adapted to co-operate with the gear teeth on the tumbler to prevent rotation of the latter, gear teeth on the sides of said bolt and a gear having a segment cut therefrom and 50 spaced to co-operate with the gears on the bolt each of said gears being adapted to have a wire attached thereto to operate a signal when the gear is rotated.

4. A lock comprising a bolt, means for reciprocating said bolt, a plurality of tumblers for preventing movement of the bolt in one direction, notches in said tumblers adapted to receive the end of the bolt, means for rotating each tumbler independently of 55 the other, gear teeth in the edges of said tumblers, gear teeth on the end of the bolt adapted to co-operate with the gear teeth on the tumbler to prevent rotation of the latter, gear teeth on the sides of said bolt, 60 a gear wheel pivotally mounted on each side of the bolt, means for rotating said gears, said gears having a segment removed therefrom and a wire attached to each of said gears, said wire extending to a signal 65 and adapted to operate the same when any one of the gears rotates.

5. A lock comprising a bolt, means for reciprocating said bolt, a plurality of tumblers for preventing movement of the bolt 75 in one direction, notches in said tumblers adapted to receive the end of the bolt, means for rotating each tumbler independently of the others, gear teeth in the edges of said tumblers, gear teeth on the end of the bolt 80 adapted to co-operate with the gear teeth on the tumbler to prevent rotation of the latter, gear teeth on the sides of said bolt, a gear wheel pivotally mounted on each side of the bolt and means for rotating said 85 gears, said gears having a segment removed therefrom, and a wire extending from each gear and adapted to operate a signal.

In testimony whereof I affix my signature.
JOSEPH A. MACK.
